(57) CLAIM

I claim the ornamental design for the perfume bottle with cap, as shown and described.

DESCRIPTION

FIG. 1 is a front view of the new ornamental perfume bottle with cap of the present invention, with the rear plan view thereof being essentially a mirror image of this view, the sole difference being the non-parallel sides as reflected in FIG. 2. FIG. 2 is a right side view thereof, with the left side view thereof being a mirror image of this view; and, FIG. 3 is a top plan view thereof.
